UNITED STATES PATENT OFFICE.

WILLIAM J. COTHRAN, OF MARTIN, GEORGIA.

WIRE-SUPPORT FOR FENCE-POSTS.

1,178,630.

Specification of Letters Patent.

Patented Apr. 11, 1916.

Application filed June 21, 1915. Serial No. 35,369.

To all whom it may concern:

Be it known that I, WILLIAM J. COTHRAN, a citizen of the United States, residing at Martin, in the county of Stephens and State 5 of Georgia, have invented certain new and useful Improvements in Wire-Supports for Fence-Posts, of which the following is a specification, reference being had to the accompanying drawings.

10 This invention relates to fence posts, and particularly to means for connecting fence wires to the posts.

The primary object of my invention is the provision of a fence post and wire connector 15 so constructed that the wire connectors may be adjusted vertically upon the post to any desired extent so as to support the wires at various heights.

20 A further object of my invention is to so construct the device which engages the wire with the fence post that the wire will be given a bend or kink which will prevent the wire from pulling through the fence post.

25 A further object of the invention is the provision of a fence post and connector for the wires thereof so formed that any number of wires may be easily applied to the fence post and these wires may be adjusted 30 nearer to or farther from each other and any of the wires may be detached at any time desired.

Other objects will appear in the course 35 of the following description.

35 My invention is illustrated in the accompanying drawings, wherein:

Figure 1 is an elevation of the post with my wire supporting attachments applied thereto; Fig. 2 is a fragmentary section on the line 2-2 of Fig. 1; Fig. 3 is a section on the line 3-3 of Fig. 2; Fig. 4 is a section on the line 4-4 of Fig. 2.

40 Referring to these figures, 2 designates a fence post which may have any desired form and be made of any suitable material, but which is so formed as to provide for a longitudinally extending slot 3 which preferably extends from a point very near to the ground to the upper end of the post, that portion of the post which is adapted to be disposed within the ground being preferably not slotted.

45 For the purpose of holding the wires in engagement with the fence post and provide for the adjustment of the wires, I provide a wire supporter and connector which

comprises a shank 4 having a width approximately that of the slot and having a head 5 whose width is greater than the width of the post and which, therefore, extends upon either side of the slot upon the front of the post. The shank 4 for a depth nearly equal to the depth of the slot 3 is flat faced on each side and then the shank is reduced and extended, this extension 6 being screw threaded for the reception of a nut 7. That portion of the shank 4 which is disposed within the slot 3 is formed with a downwardly and forwardly extending recess 8, this recess extending nearly to the head. The lower wall of this recess is transversely rounded, while the end wall of the recess is reduced in thickness and rounded as at 9. This wire supporter and connector is adapted to be disposed in any desired position in the slot 3 with the fence wire 10 disposed within the recess 8. A washer 11 is then placed over the reduced screw threaded portion 6 of the shank and the nut 7 is then placed upon the shank, as illustrated in Fig. 2, and turned up. This draws the shank into the slot 3 until the inner face of the head 5 engages against the front face of the fence post. This action deflects the wire, as at 12, see Fig. 3, so that the wire is prevented from any longitudinal movement through the post and is locked firmly therein.

It will of course be obvious that any number of connectors and supporters may be used in connection with any one post and that these connectors and supporters may be disposed in any desired relative arrangement so as to support the wires either close together or far apart, or with the lower wires close together and the upper wires far apart. It will also be obvious that the device may be used for woven wire fences, the connectors being engaged with the horizontal wires of the panel. It will be plain that by withdrawing these connectors the separate wires or an entire panel of woven wire may be readily disconnected from the post at any time desired, thus permitting the easy removal of the fence, the easy setting of it up, and the easy repair of the fence in case it is necessary. The construction is very simple, can be readily applied to fences of many different constructions, and is thoroughly effective for the purpose. At any time desired the several connectors may be loosened and the wire tightened up if

2
this becomes necessary. However, because of the binding action of the rib 9 and the crimp 12 formed in the wire, there will be very little, if any, stretching of the wire between the posts.

Having thus described my invention, what I claim is:

A fence post having a longitudinal slot and a wire engaging member coacting therewith having a shank having parallel opposite sides, the shank having a width equal to that of the slot, the outer end of the shank being formed with a head greater in width than the width of the slot and adapted to engage the front face of the post, said shank having a wire receiving recess extending inward from its upper face and forward

nearly to the head, the recess being adapted to receive a fence wire extending across the face of the post and at right angles to the shank, the wall at the end of the recess being reduced in thickness to less than the thickness of the shank and being rounded, said shank having a reduced screw threaded extension projecting beyond the post, and a nut engaging said extension and operatively engaging against the rear face of the post.

In testimony whereof I hereunto affix my signature in the presence of two witnesses.

W. J. COTHRAN.
